THERMOSTAT

George W. Whitehurst, Portsmouth, Va.

Application November 5, 1937, Serial No. 173,019

13 Claims. (Cl. 200—138)

- This invention relates to a thermostat, and aims to provide, in a manner as hereinafter set forth, a device of the class referred to which is quickly responsive to sudden changes in temperature; 5 easily and cheaply made; capable of operating in a satisfactory manner in any position which it may be set; of a size to occupy a small space; of sturdy construction; and adaptable for light and heavy work.
- 10 The invention further aims to provide, in a manner as hereinafter set forth, a thermostat capable of being used for and in connection with that type of oil burner which does not require electrical operations for control.
- 15 The invention further aims to provide, in a manner as hereinafter set forth, a thermostat which is for use on light and heavy duty circuits; capable of being adjusted to close tolerance in temperature control; and so formed to make positive quick contact, as well as opening and closing with the same degree of snap.
- 20

To the above ends essentially and to others which may hereinafter appear, the invention consists of the novel construction, combination and arrangement of parts as will be more specifically referred to and illustrated in the accompanying drawings wherein are shown embodiments of the invention, but it is to be understood that changes, 25 variations and modifications may be resorted to which fall within the scope of the invention as claimed.

In the drawings—

- Figure 1 is a side elevation of a thermostat in accordance with this invention,
- 35 Figure 2 is a top plan view thereof,
- Figure 3 is a section on line 3—3, Figure 1,
- Figure 4 is a section on line 4—4, Figure 1,
- Figure 5 is a section on line 5—5, Figure 1 when the device is adjusted for quick snap action,
- 40 Figure 6 is a section on line 5—5, Figure 1 when the device is arranged for slow action,
- Figure 7 is a section on line 7—7, Figure 1,
- Figure 8 is a section on line 8—8, Figure 1,
- 45 Figure 9 is a fragmentary view in side elevation of a modified form,
- Figure 10 is a side elevation of a modified form of thermostat, in accordance with this invention, disposed horizontally and with the housing for the elements of such thermostat illustrated in longitudinal section,
- 50 Figure 11 is a section on line 11—11, Figure 10,
- Figure 12 is a section on line 12—12, Figure 10,
- Figure 13 is a section on line 13—13, Figure 10,
- 55 Figure 14 is a section on line 14—14, Figure 10,

Figure 15 is a vertical sectional view of another modified form, and

Figure 16 is a top plan view of the structure shown in Figure 15.

Referring to Figures 1 to 8 of the drawings, the thermostat 1 illustrated thereby is adapted to be connected to a base 2 which may be of any suitable form, shown by way of example as consisting of a straplike member of angle form of the desired length and width and of rectangular contour in transverse cross section. The said member includes a pair of end parts 3, 4 disposed in parallel planes and connected together by an inclined intermediate part 5. The part 3 is of less length than part 4 and is formed with a screw-threaded opening 6 centrally thereof. The part 4 is provided with spaced aligned openings 7 for the passage of holdfast means, not shown for anchoring the base to a support.

The thermostat 1 includes a pair of thermo-static bars 8, 9 disposed in parallel spaced relation. The bar 9 is of greater length than the bar 8. The bars have their elements 10 of greatest expansion arranged on and throughout their inner sides. The bars at the end portions 11 thereof have aligned openings 12, which also align with the opening 6 in the base 2. Arranged between the end portions 11 of the bars is a spacer block 13 formed with a passage 14 having its ends aligning with the openings 12. The bars 8, 9, 30 spacer 13 and base 2 are connected together by a holdfast means 15 extending through openings 12, passage 14 and having threaded engagement with the wall of opening 6.

The bars 8, 9 are formed with aligned openings 35 16, 17 respectively. The opening 16 is of greater diameter than the opening 17. Extending through the latter and anchored to bar 9, as at 18 is an adjusting screw 19, which also extends through, projects above and is of less diameter 40 than the opening 16. Threadedly engaging with that portion of the screw 19 which projects above opening 16 is an adjusting nut 20. Surrounding the screw 19 and interposed between bar 8 and nut 20 is a coiled tensioning spring 21. The bar 45 8 in close proximity to its end 22 is provided with a pair of spaced parallel positioning pins 23 of a length to extend above and to depend below bar 8. The latter is formed with an opening 24 interposed between the opening 16 and the end 22 50 thereof. The purpose of the opening 24 will be referred to.

The bar 9 in proximity to its end 25 is formed with a screw-threaded opening 26 and inwardly adjacent the latter with an opening 27 of greater 55

diameter than the opening 26. Positioned on the inner side of bar 9 and projecting beyond the end 25 of the latter is a rectangular block 28 of insulation provided with openings 29, 30 and 31. The 5 openings 30, 31 align with the openings 26, 27 respectively of the bar 9. The block 28 is anchored to the bar 9 by a tie bolt 32 threadedly engaging with the walls of the openings 26 and 30. Extending through the opening 29, as well as threadably engaging with the block 28 is a binding post 33 provided at its upper end with a contact 34. Threadably engaging with the wall of the opening 31, extending in the opening 27 and projecting above the block 28 is a travel controlling screw 10 15 35 for a circuit opening and closing member to be referred to. The lower end of the screw 35 is spaced from the wall of opening 27. The screw 35 is of greater length than the bolt 32 and has its head 36 spaced above the block 28.

20 The thermostat 1 includes a combined snapping, snap regulating and circuit opening and closing mechanism generally indicated at 37 and which is arranged above and below the bar 8, as well as projecting from the latter to over the contact 34. The mechanism 37 is to normally engage the contact 34. The mechanism 37 includes a pair of superposed compression levers 38, 39, the former being arranged above and the latter below the bar 8 and positioned at one end between the pins 23 is a pair of oppositely disposed shifters 40, 41 of like form and each consisting of a horizontally disposed part 42 and an outwardly inclined part 43. The shifters are constructed of light spring metal and are of concavo- 25 convex contour in transverse cross section. The parts 42 of the shifters are arranged between the pins 23. The part 42 of shifter 40 is positioned on the outer side of bar 8 below the lever 38. The part 42 of the shifter 41 is positioned against the inner side of the bar 8 and above the lever 39. The parts 42 of the shifters are anchored to the bar 8 by a securing pin 44 which extends above part 42 of shifter 40 and depends below part 42 of shifter 41. The pin 44 is upset at each end 30 to provide the heads 45, 46 for a purpose to be referred to. The pin 44 extends through the levers 38, 39, which are provided intermediate their ends with openings 47, 48 for the passage of the pin 44. The heads 45, 46 provide fulcrums for the levers 38, 39 respectively. The lever 38 is formed with a screw-threaded opening 49 which aligns with the opening 24. Threadably engaging with the wall of the opening 49, extending through opening 24 and seated on lever 39 is an adjustable snap regulating screw 50.

The mechanism 37 includes a coupling block 51 of insulation material provided with a transverse groove 52 opening at its sides and at one end. The block 51 tapers in opposite directions to 60 provide points 53, and extends between and has its points 53 bear against the inner sides of the parts 43 of the shifters in proximity to the free ends of such parts. The parts 43 of the shifters are connected to the block 51 by the securing pins 65 54. The block 51 is arranged above and spaced from the block 28. Extending into the groove 52 and anchored to the block 51 by the holdfast means 55 is a circuit opening and closing member 56 of a length to extend over contact 34. The 70 member 56 is provided with an opening 57 through which extends the shank of the screw 35. The opening 57 is of greater diameter than said shank. The head 36 of the screw 35 is arranged over the member 56 and provides a stop for limiting the extent of the shift of member 56 when

the latter is moved from circuit closing position. The member 56 is provided on its inner face with a contact 58 which coacts with the contact 34 for the purpose of closing the circuit when the contacts are in engagement. A binding post 59 is 5 connected to member 56 and has its inner end provided with the contact 58.

With reference to the modified form shown in Figure 9, and indicated at 60, it is of the same construction as the form shown in Figure 1 with 10 this exception that the thermostatic bars 61, 62 have their elements 63 of greatest expansion arranged on the outer sides of the bars. Otherwise than that as stated, the form shown in Figure 9 will be the same as that shown in Figure 1.

The thermostat 1 is of a form to break the contact when a predetermined maximum degree of temperature acts thereon. The thermostat 60 is of a type to break the contact when a predetermined minimum degree of temperature acts thereon. The function referred to with respect to thermostat 1 is due to the manner in which the elements of the greatest expansion of the thermostatic bars 8, 9 are arranged on said bars. 20 The function referred to in connection with thermostat 60 is due to the manner in which the elements of least expansion of the bars 61, 62 are arranged on said bars. With respect to the thermostat 1 the elements 10 of the thermostatic bars 30 8, 9 when maximum temperature is reached will cause the non-anchored ends of the bars to move apart from each other. With respect to the thermostat 60 the elements 64 of least expansion when minimum temperature is reached will cause 35 the non-anchored ends of the bars to move apart from each other. When the non-anchored ends of the thermostatic bars move away from each other, the contacts 34, 58 are moved out of contacting relation.

The adjusting screw 19, nut 20 and spring 21 are for the purpose of adjusting or placing the thermostatic bars 8, 9 in their correct or desired position to govern a desired or certain temperature setting so that the contacts 34, 58 are opened 45 and closed at the desired temperature.

The parts 42, 43 respectively of the shifters 40, 41 are termed shanks and heads respectively. The shanks are held stationary against opposite sides of the bar 8. The levers 38, 39 act at one end thereof for compressing the body of the shifters at the point of emergence of said shanks with said heads. The heads extend from bar 8 and are inclined outwardly in opposite directions. The heads are capable of bending or snapping in unison in like directions with respect to the shanks. The bending or snapping movement of the heads is an oscillatory one and such movement provides for a snap opening or closing movement relative to the contacts 34, 58. This movement in relation to the contacts is regulated in a manner to be referred to.

The screw 50 of the mechanism 37 is for the purpose of applying varying pressure on one end of the lever 39. The purpose of this pressure variation is to provide for the ends A of the levers 38, 39 to move out relative to the shanks of the shifters to allow the full curve of the heads of the shifters to exist, and when resistance to the compression effort on the part of the levers is overcome, the heads give away with a quick snap or sudden movement. The snap of the heads is controlled by the extent of reducing the curvature of the heads. The greatest snap is had when the curvature of the shifters is as shown in Figure 5. 75

The movement of the snap gradually decreases until the shifters assume a flat cross section as shown in Figure 6. The shifters are mounted in a manner to provide a counterbalance in their resistance to each other and produce a very acute dead center or balance of effort and cannot be positioned on their dead centers. When this dead center point is reached very little effort is required to alternate the movement of the contacts to or from each other quickly and firmly, and the degree of quickness and firmness of the contact points movement can be varied by compressing the shifters until they assume a flat position such as shown in Figure 6 and then the heads possess no snapping action at all.

With reference to Figure 1, the thermostat 1 is illustrated in a near neutral position with contacts 34, 58 spaced from each other. The heat will cause the bars 8, 9 to separate at their free ends whereby member 56 will be shifted to bear against the head 36 of screw 35 and under such conditions the alternate movement of such member will be arrested and as the flexing point of the mechanism is at A the effort of the bars 8, 9 acts to break the back of shifter 40 at B and allows shifter 41 at C to straighten up and thus provides for the shifters 40, 41 to snap the contacts 34, 58 into engagement. The reverse order of operation opens the contacts.

The arrangement of the parts of the thermostat 1 provides for a sturdy construction and yet permits a very delicate and close setting of temperature control. The statement applies to the modified form shown in Figure 9.

With reference to the modified form of thermostat 65 shown in Figures 10 to 14 both inclusive, it includes a cylinder or housing 66 open at one end and closed at its other end by a cap 67. Mounted on and extended from the open end of the housing 66 is a peripherally threaded mounting nipple 68. The elements 66, 67 and 68 may be formed of any suitable material. The thermostat 65 is to be horizontally disposed and includes a depending means to be referred to for controlling a valve mechanism or other suitable device, more particularly an oil level controlling and fuel regulating mechanism for oil burners.

Arranged within the housing 66 abutting against the cap 67 and seating on the inner face of the nipple 68 is a base 69 of strap-like form of the desired thickness and width. The base 69 is of angle contour and includes an upstanding leg 70 and a horizontally disposed leg 71 having its end terminal portion 72 offset outwardly with respect to its remaining portion. The leg 70 snugly abuts against the inner face of the cap 67. A part of the leg 71 snugly abuts against the inner face of the bottom of the housing 66 and a part of the offset terminal portion of leg 71 snugly abuts against the inner face of the bottom of the nipple 68. The terminal portion 72 of the leg 71 is anchored to the nipple 68 by the holdfast means 73.

The thermostat 65 includes a pair of thermostatic bars 74, 75 disposed at parallel spaced relation and with the bar 74 projected beyond one end of the bar 75. The element of each of the bars of greater expansion is indicated at 76 and it is arranged on the inner side of each bar. The bars 74, 75 abut the leg 70 of the base 69. Interposed between said bars is a spacer block 77 of any suitable material which abuts the leg 70 of base 69. Interposed between the bar 75 and the leg 71 of the base 69 as well as abutting leg 70 is a spacer block 78 of any suitable material.

The bar 74, block 77, bar 75, block 78 and leg 71 have aligned openings 79, 80, 81, 82 and 83 respectively. The wall of the opening in the leg 71 is screw-threaded. Extending through the aforesaid aligned openings and threadably engaging 5 with the wall of the opening is a headed tie bolt 84 functioning to connect the thermostatic bars, the spacer block and the base 69 together.

Anchored to the bar 75 and extending upwardly through an opening 85 in the bar 74 is a positioning pin 86 of a diameter less than the diameter of the opening 85. Anchored at its lower end in the bar 76 in proximity to the free end of the latter is a vertically disposed adjusting screw 87 which extends upwardly through an opening 15 88 in the bar 74. Threadedly engaging with the upper portion of the screw 87 is an adjusting nut 89 and interposed between the latter and the bar 74, and surrounding the screw 87 is a coil tensioning spring 90.

The thermostat 65 includes a shifting arm 91 for the mechanism which is to be controlled by the thermostat. The arm 91 has its body formed of like material from which the bars 74, 75 are formed. The arm 91 projects outwardly from the 25 nipple 68 and is provided at its inner end with a notch 93, at its outer end with an opening 94 and intermediate its ends with an opening 95. The pin 86 extends through the notch 93 and is of less diameter than the width of such notch. 30 The screw 87 extends through the opening 95 and is of less diameter than the diameter of such opening. The arm 91 fulcrums on the free end of the bar 75.

The element 92 is shown by way of example as 35 a lift rod 96 having a peripherally threaded upper portion carrying an adjusting nut 97 for abutting the outer end of arm 91. As the elements of greatest expansion of the bars 74, 75 face each other, the heat, at and above maximum temperature causes the outer or free ends of the bars 74, 75 to separate or travel further apart. The screw 87, nut 89 and spring 90 are employed for adjusting the bars 74, 75 to provide for the thermostat to operate at any desired temperature 45 setting. The arm 91 is also a thermostatic bar, but has the element thereof of greatest expansion on its upper side. The arm 91 in proportion to the length of the part inserted between the bars 74, 75, from pin 86 to screw 88 and from the screw 50 87 to its outer end or nut 97 determines the amount of travel between the free ends of the bars 74, 75 and it also magnifies the travel at the service ends of the thermostatic bars or the element 92. The nut 97 in connection with the 55 threaded upper terminal portion of the bar 96 provides for the adjusting of the element 92 relative to arm 91 thereby providing an additional adjustment to the device which is to be controlled from element 92.

With respect to the modified form of thermostat 98 shown in Figures 15 and 16, it is of the same construction as the thermostat 65 with this exception that it is so disposed to provide for the vertical moving of the actuating or multiplying 65 movement arm 99 for the element 100 which it lifts and lowers. The arm 99 is formed of the same material as the arm 91, but it is of angle form and includes an upstanding branch 101 disposed at an inclination to the vertical and a horizontally disposed branch 102 extending outwardly 70 at right angles to the upper end of the branch 101. The element 100 is carried by the branch 102. The element 100 is of the same form as the element 92.

In Figures 15 and 16 the housing, which is vertically disposed is indicated at 103, the closure cap for one end of the housing at 104, the base 105, the thermostatic bars at 106, 107, the spacer blocks 108, 109, the adjusting means for the bars 106, 107 at 110 and the nipple at 111. The base 105 is disposed vertically, but it is of the same form as the base 69. As aforesaid, the construction of the thermostat 98 is the same as that of the thermostat 65, with the exceptions that the thermostat 98 is vertically disposed and the arm 99 which corresponds to the arm 91 is of angle contour.

With respect to the thermostat 65, when the bars 74, 75 thereof move apart at their free ends it allows for the inner end of the arm 91 where it is pressed against the inner face of bar 74 to move up and as arm 91 fulcrums on bar 76, that arm 91 at such point rocks and permits a magnified downward movement to the outer end of arm 91 and as the latter is of thermostatic bar-like form, it also adds its movement to the nut 97.

It is obvious that by placing the least expansive elements of the thermostatic bars 74, 75 face to face, and reversing the position of the greatest expansive element of the arm 91, a reverse movement of the nut 97 will occur on heat and by this arrangement control may be had for lift on cold, or for lift on heat.

30 What I claim is:

1. In a thermostat, a pair of thermostatic bars, means for anchoring one end of the bars together and for maintaining them in parallel spaced relation, one of said bars being of greater length than and extended beyond the other end of the other bar, that bar of greatest length being provided with a contact positioned beyond the bar of shortest length, and a combined snapping, snap regulating and circuit opening and closing mechanism carried by the bar of shortest length for coaction with said contact and having its operation controlled by the thermostatic movements of said bars.

2. The invention as set forth in claim 1 having said mechanism provided with controllable oppositely disposed bodily compressible shifters of concavo-convexo contour in transverse cross section.

3. The invention as set forth in claim 1 having said mechanism provided with controllable oppositely disposed bodily compressible shifters of like form and of concavo-convexo contour in transverse cross section, each of said shifters including a shank and a head, said heads moving in like direction with respect to said shanks on the operation of said mechanism.

4. The invention as set forth in claim 1 having said mechanism provided with fulcrumed pressure applying levers and oppositely disposed shifters of like form and of concavo-convexo contour in transverse cross section having their movement controlled by said levers.

5. In a thermostat, a pair of thermostatic bars, means for anchoring one end of said bars together and for maintaining the bars in parallel spaced relation, one of said bars being of greater length than and extended beyond the other end of the other bar, said bar of greatest length being provided with a contact positioned beyond the bar of shortest length, and a combined snapping, snap regulating and circuit opening and closing mechanism carried by the bar of shortest length and including a circuit opening and closing member provided with a contact for coaction with the other of said contacts.

75 6. The invention as set forth in claim 5 having

said mechanism provided with controllable oppositely disposed bodily compressible resilient shifters of concavo-convexo contour in transverse cross section, said shifters being connected with said member.

7. In a thermostat, a pair of spaced thermostatic bars, means for anchoring one end of the bars together and for maintaining the bars in spaced relation, one of said bars being of greater length than and extended beyond the other end of the other bar, said bar of greatest length being provided with a contact outwardly adjacent the bar of shortest length, and a combined snapping, snap regulating and circuit opening and closing mechanism carried by the bar of shortest length for coaction with said contact and including resilient pressure controlled shifters, said mechanism having its operation controlled by the thermostatic movements of said bars.

8. In a thermostat, a pair of thermostatic bars, means for anchoring one end of the bars together and for maintaining the bars in parallel spaced relation, a resilient setting structure for said bars, said structure being anchored to one of the bars, extending through the other bar and bearing on the latter, a positioning pin anchored to one of said bars and extending through the other, and a multiplying arm having its body corresponding to the body of either of said bars, said multiplying arm extending between said bars and projecting from the other ends of the bars, said arm at its inner end bearing against said pin, mounted intermediate its ends on an element of said structure and having its outer end provided with an opening for the reception of a controlling element, said arm bearing at its inner end against the inner face of one of said bars and bearing intermediate its ends upon the other of said bars.

9. In a thermostat, a pair of thermostatic bars, means for anchoring one end of the bars together and for maintaining the bars in parallel spaced relation, a resilient setting structure for said bars, said structure being anchored to one of the bars, extending through the other bar and bearing on the latter, a positioning pin anchored to one of said bars and extending through the other, and a multiplying arm having its body corresponding to the body of either of said bars, said multiplying arm extending between said bars and projecting from the other ends of the bars, said arm at its inner end bearing against said pin, mounted intermediate its ends on an element of said structure and having its outer end provided with an opening for the reception of a controlling element, said arm bearing at its inner end against the inner face of one of said bars and bearing intermediate its ends upon the other of said bars, said arm being formed of a pair of branches disposed in angular relation.

10. In a thermostat, a pair of thermostatic bars, means for anchoring one end of the bars together and for maintaining the bars in parallel spaced relation, a positioning pin anchored to one of said bars and extending through an opening in the other of said bars, said pin being of less diameter than said opening, a resilient setting structure for said bars, said structure including an element anchored at one end to one of the said bars and extending through an opening in the other of said bars and with such opening being of greater diameter than said element, and a multiplying arm of thermostatic characteristics extending between and projecting from said bars for operating a controlling element, said arm having its inner end bearing against the inner face of one of said

- bars and at a point adjacent its inner end bearing against the inner face of the other of said bars, said arm having its inner end bearing against said pin and adjacent its inner end formed with an opening for the passage of said element and with the opening being of greater diameter than the diameter of said element.
11. In a thermostat, a pair of thermostatic bars, means for anchoring one end of the bars together and for maintaining them in parallel spaced relation, one of said bars being of greater length than and extended beyond the other end of the other bar, that bar of greatest length being provided with a contact positioned beyond the bar of shortest length, a contact means for coaction with said contact, a carrier for said means, a snapping structure extended from said bar of shortest length, said structure being secured to and for imparting a snapping action in opposite directions to said carrier for moving said means into and out of contacting relation with respect to said contact, and an adjustable pressure applying means for regulating the snapping movement of said structure.
12. In a thermostat, a pair of thermostatic bars, means for anchoring one end of the bars together

and for maintaining them in parallel spaced relation, one of said bars being of greater length than and extended beyond the other end of the other bar, that bar of greatest length being provided with a contact positioned beyond the bar of shortest length, a contact means for coaction with said contact, a carrier for said means, a snapping structure extended from said bar of shortest length, said structure being secured to said carrier for imparting a snapping action in opposite directions thereto to provide for the carrier moving said means into and out of contacting relation with respect to said contact, and a pair of oppositely disposed adjustable pressure applying levers arranged relative to said structure for regulating the snapping movement of the latter.

13. The invention as set forth in claim 1 having said mechanism provided with bodily compressible shifters moving simultaneously in like direction and of concavo-convexo contour in transverse cross section, and a pair of oppositely disposed fulcrumed adjustable pressure applying levers bearing on said shifters for regulating the movement of the latter.

GEORGE W. WHITEHURST.
